UNITED STATES PATENT OFFICE.

THOMAS F. GAYNOR, OF LOUISVILLE, KENTUCKY, ASSIGNOR TO THE
GAYNOR ELECTRIC COMPANY, OF SAME PLACE.

ELECTRO-MECHANICAL TRIPPING-MACHINE.

SPECIFICATION forming part of Letters Patent No. 414,695, dated November 12, 1889.

Application filed September 2, 1889. Serial No. 322,790. (No model.)

To all whom it may concern:

Be it known that I, THOMAS F. GAYNOR, a citizen of the United States, residing at Louisville, in the county of Jefferson and State of Kentucky, have invented certain new and useful Improvements in Electro-Mechanical Tripping-Machines, of which the following is a specification.

My invention relates to improvements in that class of electro-mechanical tripping-machines in which a weight is held in suspension in such a manner as that when released by the movement of the armature of the electro-magnet said weight in falling is made to trip or set free trap-doors, horse-hitching straps, doors, and other apparatus in use in fire-engine houses and the like. In using machines of this character it is customary to connect the electro-magnets in circuit with a fire-alarm signal mechanism, or else to place them in a local circuit which is operated by a relay mechanism which is in the circuit with said fire-alarm mechanism. By this arrangement, when the first impulse of the signal is sent into the engine-house, the electro-magnet of the tripping-machine becomes energized, which, through the armature mechanism, allows the suspended weight to fall, and thus automatically open the engine-house doors and release the horses, so that the fire apparatus may be brought to the scene of the fire as quickly as possible.

The object of my invention is to improve the construction of such machines, which I attain by the mechanism illustrated in the accompanying drawings, in which—

Figure 1 is a front elevation of the machine. Fig. 2 is a side elevation of the weight and slide, being shown separate from the other parts of the machine. Fig. 3 shows a vertical section of a part of the machine through the center of the guide-post and on a plane parallel with its base-plate. Fig. 4 represents a cross-section of Fig. 1 on the line *a b*, looking upwardly. Fig. 5 represents a front elevation of a modification of the lever mechanism of the machine. Fig. 6 represents a side elevation of Fig. 5. Fig. 7 represents a cross-section of Fig. 5 on the line *c d*. Fig. 8 represents a cross-section of Fig. 5 on the line *e f*.

Similar letters refer to similar parts throughout the several views.

A represents the base-plate of the machine, and is provided with lugs *A' A²*, between which a cylindrical guide-post *B* is fitted. The ends 55 of the post *B* are tapped to receive the screws *B' B²*, which secure the post in permanent position. The post *B* is grooved longitudinally, as seen at *B³* in Figs. 3 and 4, so as to admit a detent-lever *C'*, with its retracting-spring *C*, 60 to fit therein. The post *B* is also splined longitudinally upon the outside, as seen at *B⁴*, Fig. 4. The post *B* is further provided at its lower end with notches *B⁵ B⁶*, and it is further provided with a binding-screw *B⁷* at the 65 bottom of the groove *B³*, to which the lower end of the retracting-spring *C* is secured. The detent-lever *C'* is pivoted on the pivot *C²* to the post in such a manner as to admit of its movement from the position shown in Fig. 70 1 to the position in Fig. 3.

D represents a cylindrical sleeve, which is loosely fitted upon the post *B*, and is provided with perforated lugs *D' D²* and a lifting-hook *D³*. A chain or rope *E* is connected to the 75 lower lug *D²* of the sleeve *D*, and also to the weight *F*. The sleeve *D* is also provided with a feather-pin *F'*, as seen in Fig. 4, which fits in the spline *B⁴* of the post *B*, so that while admitting of a vertical motion of the 80 sleeve it prevents any rotary movement of the said sleeve *D* upon the post *B*, that the lugs and lifting-hook may always be maintained in a proper position in the front of the machine.

Around the lower end of the post *B* a ring *G*, of rubber or other elastic material, is placed as a cushion to lessen the concussion of the sleeve *D* when the latter drops down.

H represents the armature of an electro-magnet, which is pivoted at one end upon the stud *H'*, and is provided with an armature-retracting spring mechanism of the usual well-known construction, and needs no further description. The armature *H* is provided with 90 a fork-shaped trigger or catch *H²*, extending at right angles therefrom. The trigger or catch *H²* is provided with two shoulders *H³ H⁴*, (seen in Figs. 1 and 6,) which form seats for the end *C³* of the detent-lever *C'* to rest 100

upon when the latter is in the position shown in Figs. 1 and 4, and the armature is drawn back from the cores of the magnet I I.

The adjustment-screw J controls the movement of the armature in one direction, while the cores of the electro-magnet control its movement in the other direction.

In Figs. 1, 3, and 4 the detent-lever is shown as pivoted to the guide-post, while in Figs. 5 5 and 6 it is shown as being pivoted to the base-plate. When the machine is made in this latter form, the groove B³ in the post B is omitted; but a rib D⁴ is made a part of the sleeve D, and is provided with a roller D⁵ and a pivot D⁶ for said roller. The end C³ of the detent-lever is beveled, so as to support the sleeve through the roller when the lever is locked by the trigger mechanism; but when the lever is released the relation which the 20 roller and the beveled face of the large end of the lever bears to the pivot-stud C⁴ is such with reference to each other that the weight of the sleeve causes the lever to assume the position shown by the dotted lines, when the 25 end C³ of the detent-lever clears the rib D⁴ of the sleeve D, and allows the latter to drop down to a position similar to that shown in Fig. 3. In Figs. 7 and 8 the rib and roller mechanism can be more clearly seen.

30 The operation of the machine may be described as follows: When an electric impulse is sent through the electro-magnet, it causes the armature, which in an open circuit would be normally in the position shown by the full lines in Fig. 1, to assume the position shown by the dotted lines. The weight of the sleeve mechanism being greater than the retracting power of the retracting-spring of the detent-lever will cause the detent-lever to assume 35 the position shown in Fig. 3 as the sleeve drops down upon the rubber cushion, which arrests its further downward motion, the power of the sleeve in falling being determined by the amount of weight suspended 40 thereto. The cord K, which is connected to the upper lug B' of the sleeve, leads to the releasing mechanism of the apparatus to be operated, so that when the sleeve falls it imparts a sudden pull to the cord K, thus effecting 45 the purpose desired. A pin passing through a staple is usually connected to the other end of the cord K. Said pin may either secure a hasp of a door, which when released is thrown open by a door-spring, or it may 50 pass through a hole in the loop of a horse-hitch line passing through a staple, and thus liberate a horse; or it may be used for any similar purpose where only the release of a pin would be all that is necessary to accomplish 55 the object desired. If the device is to be used on a normally-closed circuit, it will only be necessary to project the shoulders of the fork-shaped armature-extension from the 60 opposite side of said armature-extension to 65 that shown in the drawings.

By the form of construction shown in Figs. 1, 3, and 4 it will be seen that the detent-le-

ver is closed into the groove of the post as the sleeve drops down, and it remains in that position until the latter is lifted up again, when 70 it is thrown in locking contact with the armature-fork by the tension of the retracting-spring, to be then held up until it is again released by the movement of the armature responding to another signal sent through the 75 magnet. On account of the beveled face H⁵ of the armature-fork, the latter yields to the upward pressure of the detent-lever as the latter assumes the horizontal position when the sleeve is lifted up by the lifting-hook; 80 but when the hook is released the downward movement of the detent-lever is arrested by the seats of the fork, securing the end of said lever and thereby holding the sleeve up.

Figs. 5, 6, 7, and 8 show the employment of 85 a form of leverage to hold the sleeve up of a different order to that shown in Figs. 1, 3, and 4. As a consequence, the groove B³ is dispensed with in the post, and the rib D⁴, with the friction-roller D⁵, is added to the sleeve 90 D and the rib made integral therewith. The movement of the catch end of the detent-lever is also of a much shorter arc, while the retracting-spring is connected to the base-plate instead of to the post. The action of the catch 95 end of the lever and the armature-fork catch which locks it up is similar in both forms of construction.

The essential principle desired in the device is to permit of having a comparatively 100 heavy weight locked up by the detent-lever, and yet so arrange the leverage upon the lever as to minimize the pressure of the catch end of the lever upon the seats forming the catch of the armature-fork, so that a minimum of battery-power will, through the magnet, trip the weight free to drop and accomplish the purpose intended, all of which is attained by the device herein shown and described.

110 This machine has been referred to as being a device adapted to fire-engine houses. It can also be used for all other purposes where it is necessary to liberate, actuate, or release any device or apparatus, and where it 115 is desirable to accomplish the purpose electrically and automatically—as, for instance, to pull the cord of a steam-whistle, or release a visual signal, or turn a gas-pipe valve, or the like.

120 Having thus described my invention, what I claim, and desire to secure by Letters Patent, is—

1. In an electro-mechanical tripping-machine, the combination of a base-plate provided with perforated lugs, a guide-post secured to said lugs by binding-screws and provided with a longitudinal groove and a longitudinal spline, a sleeve shorter than said guide-post and loosely fitted thereto and provided with two perforated lugs, a lifting-hook and a pin therein fitted to the spline in the aforesaid guide-post, and a weight connected to one of the lugs of the aforesaid

sleeve, a detent-lever pivoted to the aforesaid post, so as to close into the groove therein, and an armature pivoted to the aforesaid base-plate, having a forked extension provided with catch-seats adapted to lock the free end of the aforesaid detent-lever when the latter is in proper connection therewith, an adjusting-screw secured to said base-plate, so as to regulate the movement of said armature, and an electro-magnet secured to said base-plate in such a position as to actuate said armature when energized by an electric current, substantially as specified.

2. In an electro-mechanical tripping-machine, the combination of an electro-magnet, a weight mechanism, a detent-lever adapted to hold in a suspended position said weight mechanism, and a pivoted armature having a fork-shaped catch-extension provided with seats which are adapted to engage with and lock up the end of the said detent-lever, and

being provided with a retracting-spring and an adjusting-screw, by means of which its movement can be regulated, substantially as specified.

3. In an electro-mechanical tripping-machine having an electro-magnet and an armature provided with a catch mechanism, a detent-lever adapted to engage said armature with said mechanism, and a guide-post mechanism, the combination therewith of a sleeve having a rib D⁴ and a friction-roller D⁵, and being provided with a weight which is connected thereto and having a cord K connected thereto, and being adapted to be held up or released by the aforesaid detent-lever, in the manner set forth, substantially as specified.

THOMAS F. GAYNOR.
